UNITED STATES PATENT OFFICE.

JOHN E. REDIN, OF ROCKFORD, ILLINOIS, ASSIGNOR OF ONE-HALF TO CHARLES A. LINDEBERG, OF ROCKFORD, ILLINOIS.

LATCH.

1,111,235.

Specification of Letters Patent.

Patented Sept. 22, 1914.

Application filed January 2, 1914. Serial No. 810,016.

To all whom it may concern:

Be it known that I, JOHN E. REDIN, a citizen of the United States, residing at Rockford, in the county of Winnebago and State of Illinois, have invented a new and useful Latch, of which the following is a specification.

The present invention appertains generally to latches, and relates more particularly to furniture latches.

It is the object of the present invention to provide a novel and improved latch for the drawers, doors and other moving parts of furniture, such as desks, cabinets, and other house and office furniture.

Another object of the present invention is to provide a latch of that character which shall be readily applicable to various objects, and without the necessity of screws, 20 nails or other securing members being employed.

A further object of the present invention is to provide a device of the nature indicated which shall be comparatively simple, durable, substantial, compact and inexpensive in construction, as well as serviceable, convenient and efficient in its use.

With the foregoing and other objects in view, which will be apparent as the nature 30 of the invention is better understood, the present invention resides in the combination and arrangement of parts and in the details of construction hereinafter described and claimed, it being understood that changes in 35 the precise embodiment of the invention herein disclosed can be made within the scope of what is claimed without departing from the spirit of the invention.

The invention has been illustrated in several 40 of its preferred embodiments, in the accompanying drawing, wherein similar reference characters have been employed to denote corresponding parts, and wherein:

Figure 1 is a section of one form of the 45 device, the section being taken approximately on the central or median plane. Fig. 2 is a sectional detail taken on the line 2-2 of Fig. 1. Fig. 3 is a fragmental detail of the form illustrated in Fig. 1. Fig. 4 is a 50 view similar to Fig. 1 of a second modification. Fig. 5 is a view similar to Figs. 1 and 4, of another variation. Fig. 6 is a view similar to Fig. 1, illustrating another modification. Fig. 7 is a rear view of the modified form illustrated in Fig. 6. Fig. 8 is a 55 sectional view taken on the line 9-9 of Fig. 6.

In carrying out the invention, reference being had in detail to Figs. 1, 2, and 3, there is provided a latch bolt tube 1, and a plunger tube 2, which are adapted to intersect each other when applied to an object. These tubes 1 and 2 are preferably of like diameter, the tube 2 being provided adjoining its inner or lower end with rectangular openings 3 60 in its opposite sides, and opposite sides of the tube 1 being flat as at 4, from the rear or inner end of the tube 1 to a point short of its outer or front end to provide the shoulders 5. The rear or inner end of the 65 bolt tube 1 is adapted to be inserted through the openings 3 of the tube 2, the tubes being at right angles with respect to each other, and the flat sides 4 of the tube 1 permitting the said tube to be passed through the openings or slots 3 of the tube 2 in the manner specified. When the tube 1 is inserted 70 through the tube 2, the shoulders 5 are adapted to seat against the tube 2 at the edges of the respective opening 3, to limit 75 the inward movement of the tube 1.

The tube 1 is provided with an upper longitudinal slot 6 within the tube and with a similar lower slot 7, the tube 2 being provided at its rear side with a longitudinal slot 85 8 intersecting the respective opening 3, and extending from the lower or inner end of the tube 2 to a point slightly above the respective opening 3.

The latch bolt 9 is preferably of circular 90 cross section so as to fit snugly in the tube 1, with its inner end spaced from the inner end of the tube 1 and with its outer end adapted to be projected from and retracted into the forward or outer end of the said tube. The 95 latch bolt 9 is provided with an opening or slot 10 adjoining the tube 2 and a coiled wire spring 11 is housed within the inner or rear portion of the tube 1 in back of the latch bolt 9 to project or shoot the same. 100 The rear or inner end of the tube 1 is preferably closed to provide a seat for the respective end of the spring 11, although any other suitable seat or bearing for the spring may be provided at the inner end of the said 105 tube, the other end of the spring bearing against the inner end of the latch bolt to create a tension thereagainst.

A plunger or actuating member 12 is slidably disposed within the tube 2, the said 110

plunger being preferably stamped from a bar or plate of suitable sheet metal or other material, although it may be otherwise fashioned. The plunger 12 is provided with the lower inclined end 13 providing a cam, the tip of which passes through the upper slot 6 of the tube 1 and partially enters the opening or slot 10 of the latch bolt. At the heel of the inclined or cam end 13 of the plunger, the same is provided with a shoulder or stop 14 adapted to strike the upper or outer end of the slot 8 when the plunger is moved upwardly or outwardly, as seen in Fig. 1. The shoulder or stop 14 is adapted to move within the slot 8, it being noted that the said slot extends to the respective end of the tube 2 to permit of the convenient insertion of the plunger 12 prior to the engagement of the tube 1 through the tube 2.

20 A suitable wooden or other knob or finger hold 15 is secured over the outer or upper end of the tube 2, this being readily accomplished by threading the knob 15 over the tube 2.

25 In applying the said latch to an object, such as illustrated at 16, in Figs. 1 and 2, in order that the object or part 16 may be latched to an adjoining object or part 17, a bore 18 is drilled into the part 16 away from the part 17, and a second bore 19 is drilled into the part 16 at right angles to the bore 18, and so as to intersect the last mentioned bore. The part 17 is provided with a keeper or socket 20, for the reception of the latch bolt 9 when it is projected by the spring 10. The tube 2 with the plunger 12 inserted therein, is inserted into the bore 19 so that the openings 3 register with the bore 18, and the tube 1 is then inserted into the last mentioned bore, so as to pass through the openings 3. The spring and latch bolt may be introduced into the tube 2 either before or after the insertion of the tube 1 within the bore 18, the tip of the plunger 12 being adapted to engage within the slot or opening 10 of the latch bolt. When the tube 1 of the part 16 registers with the keeper or socket 20 of the part 17, the latch bolt 9 will be projected into the keeper or socket by the spring 11, the plunger 12 being in raised position, as seen in Fig. 1. By pressing the plunger 12 inwardly or downwardly, the cam 13 will ride against the inner end of the slot or opening 10 of the latch bolt, and consequently, the latch bolt will be retracted from the keeper or socket 20 to permit the parts 16 and 17 to separate. It will thus be apparent that the latch bolt may be readily operated through the medium of the plunger 12.

When the tubes 1 and 2 are inserted in the manner specified, it will be apparent that the tube 1 will lock the tube 2 within the respective bore 19, the tube 1 also being frictionally held in position so that the tubes

may be engaged to the object or part 16 without the employment of screws or other securing members. The tubes are also easily and quickly applied to the object by simply drilling the bores into the object at right angles so that the bores intersect. It is preferable to have the knob 15 flush with the object 16, although this is not essential.

In the form illustrated in Fig. 4, the general construction is somewhat the same as the form above described. The tube 2^a is inserted into the bore 19^a drilled in the object 16^a, the tube 1^a being slightly smaller in diameter than the tube 2^a adjoining its inner or lower end and being inserted through the openings 3^a in the tube. The tube 1^a is provided with the upper and lower slots or openings 6^a and 7^a respectively, within the tube 2^a and the tube 2^a is provided with the rear longitudinal slot 8^a extending from its inner or lower end to a point short of the outer end.

The latch bolt 9^a is hollow and preferably has its inner or rear end open. The latch bolt 9^a is provided with a longitudinal slot 10^a in its upper side adjoining its inner end, and a coiled wire spring 11^a is housed within the latch bolt, the forward end of the spring seating against the forward end of latch bolt, and the rear end of the spring being engaged by an ear or finger 22^a struck inwardly from the bottom of the tube 1^a at the forward end of the slot 7^a through a lower slot 21^a provided in the latch bolt. The spring 11^a being under compression presses the latch bolt outwardly or forwardly to project the latch bolt into the proper keeper or socket (not shown).

The plunger 12^a is slidable within the tube 2^a and the knob 15^a which is engaged to the tube and which projects beyond the tube, the inner or lower end of the plunger 12^a being provided with an inclined or beveled portion 13^a, forming a cam, the tip of which enters the slot 10^a of the latch bolt, so that when the plunger is depressed or forced inwardly, the latch bolt will be retracted inasmuch as the cam 13^a works against the inner end of the slot 10^a. The plunger 12^a is provided with the shoulder or stop 14^a working within the slot 8^a and seated against the outer end of said slot when the plunger is slid outwardly or upwardly.

Inasmuch as the form of latch illustrated in Fig. 4 operates in a manner similar to the form illustrated in Figs. 1 and 2, further description thereof is not deemed necessary, the tubes 1^a and 2^a also being inserted in the object in the manner of the tubes 1 and 2 above described.

In the variation illustrated in Fig. 5, the tube 2^b is inserted into the bore 19^b of the object 16^b and the tube 1^b is inserted into the bore 18^b of the said object through circular openings 3^b provided in the tube 2^b,

the tube 1^b being preferably of slightly smaller diameter than the tube 2^b. The tube 1^b is provided with the upper and lower longitudinal slots or openings 6^b and 7^b respectively, while the tube 2^b is provided with the longitudinal rear slot 8^b intersecting the respective opening 3^b. A latch bolt 9^b is slidably snugly within the tube 1^b, and is provided with a diagonal opening or passage 10^b therethrough adjoining its rear or inner end.

The plunger embodies a stem 12^b having a finger piece 24^b threaded onto its outer or upper end and working snugly within the knob 15^b, the lower or inner end of the stem 12^b being provided with a circular head 23^b working snugly within the tube 2^b. The head 23^b is provided with a depending diagonal finger 13^b, the tip of which enters the diagonal opening or passage 10^b of the latch bolt, in order that when the plunger, or finger piece 24^b thereof, is depressed or forced inwardly the latch bolt will be retracted. The heel of the finger 13^b is provided with a shoulder or stop 14^b working within the slot 8^b. Ears 22^b are struck inwardly from the tube 2^b, a coiled wire spring 11^b surrounding the stem 12^b and terminally engaging the ears 22^b and the finger piece 24^b to normally raise the plunger, to thereby project the latch bolt.

From the foregoing, taken in connection with Fig. 5, the operation of the device will be clearly apparent without further detailed description.

In the modification illustrated in Figs. 7, 8 and 9, the general construction is something similar to the form illustrated in Fig. 1. The tube 2^d is inserted into the bore 19^d drilled in the object 16^d, the tube 1^d which fits in the bore 18^d being slightly smaller in diameter than the tube 2^d, and the tube 2^d having circular openings 3^d adjoining its inner or lower end, through which the tube 1^d is passed. The tube 1^d is provided with the upper and lower longitudinal slots 6^d and 7^d within the tube 2^d, and the tube 2^d is provided with a longitudinal rear slot 8^d intersecting the rear opening 3^d, and extending to the inner or lower end of the tube 2^d. The latch bolt 9^d is slidably snugly within the tube 1^d, and is provided with a reduced portion 9' intermediate its ends, and forming a shoulder 9''. The reduced portion 9' of the latch bolt is provided with a slot 10^d, and the tube 1^d is provided with instruck ears or lugs 22^d entering the slot 10^d of the latch bolt at the outer ends of the slots 6^d and 7^d. A coiled wire spring 11^d surrounds the reduced portion 9' of the latch bolt and is terminally seated against the shoulder 9'' and the ears 22^d, to yieldingly shoot the latch bolt, the free end of the latch bolt being preferably curved in order that the latch bolt may snap into

engagement with the keeper when the door or other object 16^d is closed or swung toward the keeper.

The flat plunger 12^d which is slidable in the tube 2^d is provided at its lower end with a bevel 13^d, the tip or nose of the plunger 12^d entering the slot 10^d of the latch bolt and passing through the slot 6^d of the tube 1^d. The plunger 12^d is provided with a stop or lug 14^d at the heel of the bevel or cam 13^d, which stop or lug slidably engages through the slot 8^d of the tube 2^d. The push button or finger piece 24^d is slidable in the mouth or outer end of the tube 2^d, and is threaded over the stem or shank 12' of the plunger 12^d, whereby the plunger may be readily pressed or forced inward to retract the bolt.

The end of the slot 8^d of the tube 2^d is offset, as at 8', to form the shoulder 8'', against which the stop or lug 14^d is normally adapted to rest, to prevent the tip or nose of the plunger from disengaging the slot 10^d, which would permit the latch bolt to be withdrawn. By springing or twisting the plunger 12^d, however, the stop or lug 14^d may be sprung into the offset end 8' of the slot 8^d, so that the plunger 12^d may be slid upwardly out of engagement with the latch bolt, whereby the latch bolt 9^d and tube 1^d may be withdrawn from the tube 2^d.

From the foregoing taken in connection with the drawing, it will be manifest that various forms of latch bolts may be provided, and that various means may be provided for actuating the latch bolts, it being understood, that the present invention is susceptible of numerous alterations and modifications within the scope of the appended claims, without departing from the spirit of the invention.

Having thus described the invention, what is claimed as new is:

1. In a latch, a tube having diametrically opposite openings, a second tube inserted through the said openings, a latch bolt slidably within the second tube, the first mentioned tube having a longitudinal slot extending from one end beyond the said openings, and a plunger slidable in the other end portion of the first-mentioned tube, and having its inner end operatively engaged with the latch bolt, the plunger having a stop engaging in the said slot to limit the movement of the plunger away from the latch bolt.

2. In a latch, a tube having diametrically opposite openings, a second tube inserted through the said openings, a latch bolt slidably in the second tube and having a slot, the first mentioned tube having a longitudinal slot extending from one end and intersecting one of the said openings, and a plunger slidable in the other end portion of the first mentioned tube and having a flat

cam portion at its inner end and a stop at the heel of the cam portion engaging the said slot of the first mentioned tube, the tip of the cam portion engaging the said slot of 5 the latch bolt.

3. In a latch, a tube having diametrically opposite openings, a second tube inserted through the said openings, a latch bolt slideable in the second tube, the first mentioned 10 tube having a longitudinal slot extending from one end beyond the said openings, and a plunger slideable in the other end portion of the first mentioned tube and having its inner end portion operatively engaged with 15 the latch bolt, the plunger having a stop engaging within the said slot, and the end of the slot having an offset portion forming a shoulder against which the stop is seatable to retain the plunger in operative engagement with the latch bolt, and to receive the 20 stop when the plunger is turned to withdraw the plunger out of engagement with the latch bolt.

4. In a latch, a tube having diametrically 25 opposite openings, a second tube inserted

through the said openings, a latch bolt slideable in the second tube and having a slot, the first mentioned tube having a longitudinal slot extending from one end and intersecting one of the said openings, and a plunger slideable in the other end portion of the first mentioned tube and having a flat cam portion at its inner end and a stop at the heel of the cam portion engaging the said slot of the first mentioned tube, the tip of 30 the cam engaging the said slot of the latch bolt, and the end of the slot having an offset portion forming a shoulder against which the stop is seatable to retain the tip of the cam portion in engagement with the 35 latch bolt slot, and to receive the stop when the plunger is turned to withdraw the tip of the cam portion from the latch bolt slot.

In testimony that I claim the foregoing as my own, I have hereto affixed my signature in the presence of two witnesses.

JOHN E. REDIN.
